US00D821522S

(12) **United States Design Patent** (10) **Patent No.:** **US D821,522 S**
Robinson (45) **Date of Patent:** **** Jun. 26, 2018**

(54) **FLOTATION DEVICE**

(71) Applicant: **The MCR Group, LLC**, Knoxville, TN (US)

(72) Inventor: **Phillip Robinson**, Knoxville, TN (US)

(73) Assignee: **THE MCR GROUP, INC.**, Knoxville, TN (US)

(**) Term: **15 Years**

(21) Appl. No.: **29/580,748**

(22) Filed: **Oct. 12, 2016**

(57) **CLAIM**

I claim the ornamental design for a flotation device, as shown and described.

DESCRIPTION

FIG. 1 is a top perspective view of a flotation device of the new design;

FIG. 2 is a bottom perspective view thereof;

FIG. 3 is a top view thereof;

FIG. 4 is a bottom view thereof;

FIG. 5 is a left side view thereof;

FIG. 6 is a right side view thereof;

FIG. 7 is a rear view thereof;

FIG. 8 is a front view thereof;

FIG. 9 is a top perspective view of a flotation device of the new design;

FIG. 10 is a bottom perspective view thereof;

FIG. 11 is a top perspective view of a flotation of the new design; and,

FIG. 12 is a bottom perspective view thereof.

The portions of the Figures shown in broken lines having a dash-dash pattern are for illustrative purposes only and form no part of the claimed design.

The portions of the Figures shown in broken lines having long and short dashes define the bounds of the claimed design and form no part thereof.

1 Claim, 10 Drawing Sheets
